SLUSHER BUCKET

John O. Pitts, Grand Junction, Colo.

Application December 27, 1948, Serial No. 67,370

4 Claims. (Cl. 37—135)

1

This invention relates to a hoist-operated bucket for use with a portable hoist in a mine for dragging rock and ore upon a loading ramp or chute for loading the mine cars. The hoist ropes and bucket are sometimes called muckers, scraper haulers, or drag scrapers, although the general term for the entire rig is a "slusher," and the bucket is generally known as a "slusher bucket." In many mines the ore bodies are inclined and are worked from above, and in such cases it is impossible to place the bucket below the load so that it will fill when drawn upward, as is usual with dragline buckets.

The principal object of this invention is to provide a bucket which will fill while being drawn downwardly along an inclined mine stope and which, when filled, can be turned over for the return trip up the grade without spilling the contents.

A further object is to so construct the bucket that it can be efficiently operated from a standard, portable, three-drum slusher such as used in mining operations, and to provide effective means for preventing the contents from rolling from the open end of the bucket during the down-hill filling operation.

A still further object is to provide a bucket of this type with levers or runners which can be operated from the slusher to tilt or incline the bucket at any desired digging angle.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a perspective view of the improved bucket as it would appear when traveling forwardly for filling;

Fig. 2 is a plan view thereof;

Fig. 3 is a sectional view of the improved bucket, taken on the line 3—3, Fig. 2; and

Figs. 4, 5, and 6 are diagrammatic views illustrating the improved bucket in use.

The improved bucket consists of two side walls 10 joined by a curved plate which forms a top 11, a bottom 12, and a curved end 13. The top 11 is shorter than the bottom 12, and the forward edges of the side walls 10 are inclined rearwardly to accommodate the difference in length

between the top and bottom, and to provide a forward cutting edge 14 on the bottom 12. The entire assembly is welded together to form a complete, integral unit.

The bucket is designed to be operated by a standard, portable, three-drum hoist or slusher, indicated at 15, Fig. 4. A wire rope leads from each of the three drums, a lead rope 16, a return rope 17, and a tail rope 18. The lead rope 16 is strained about a lead sheave 19, usually anchored in the breast of the stope ahead of the bucket.

The bucket is provided with a U-shaped bail 20, having a bridge and arms extending rearwardly from the bridge along both sides of the bucket and are pivotally mounted at each side on a pivot stud 21 projecting outwardly from each of the side walls 10. The legs of the bail have an approximate S-shape and extend rearward from the pivot studs 21 to form trailing extremities 22.

15 The forward portions of the bail legs are curved downwardly and upwardly to pass beneath stop members 23, which project outward from each side wall 10 forwardly of the pivot studs 21, and to provide a curved riding surface 24.

20 The extremity of the return rope 17 is connected with a bridle 25 having its ends attached to the extremities of the bail 20 through the medium of suitable cable loops 26. The extremity of the lead rope 16 is looped through a cable eye

25 at the middle of the bail 20 and secured by means of suitable U-bolts 27. The extremity of the tail rope 18 is connected to the middle of the curved end 13 in any desired manner, such as by

30 passing it about a cross bolt 29 inset in the end 13 and securing it by means of U-bolts 30, as shown in Fig. 3.

35 The top 11 is provided with two spaced-apart, laterally-extending roller shafts 28 mounted in suitable bearing ears on the side walls 10. Each roller shaft carries a pair of spaced-apart rollers 29. The rollers on the rearmost shaft 28 ride in a roller indentation 30 in the top 11.

40 A damper shaft 31 extends across the open mouth of the bucket. The extremities of the shaft 31 are removably mounted in receiving yokes 32 in which they are removably held by means of cotter keys 33. The shaft 31 is positioned closer to the bottom 12 than to the top 11, and carries a swinging damper plate 34 which

45 normally rests on the bottom 12 and which can swing upwardly and outwardly past the top 11.

50 The bucket is more particularly designed for operation in an inclined stope, such as indicated at 35 in Figs. 4, 5, and 6, for carrying muck, such as indicated at 38, to a hopper opening 36 for

dumping into cars 37. In such a stope it is impossible to place the bucket below the muck 38 for drawing the latter upwardly to the hopper opening 36. With the improved bucket, however, the bucket is filled as it moves downwardly into the muck.

In Figs. 4, 5, and 6 the operation of the improved bucket has been diagrammed. The bucket is first drawn downwardly into the muck 38 in the stope 35 by means of the lead rope 16, as shown in Fig. 4. The muck travels into the bucket, forcing the damper plate to swing rearwardly. The material cannot roll forwardly from the bucket, due to the checking action of the damper plate.

The bucket is retarded and guided in its downward path by means of the tail rope 18 and the braking equipment on the hoist 15. The tail rope prevents the bucket from turning sidewardly or rolling over during its downward course.

Should it be desired to take a deeper bite of material, the operator can increase the tension in the return rope 17, causing the forward extremity of the bail 20 to be lifted, and causing the trailing extremities 22 to engage the ground surface to tilt the rear extremity of the bucket upwardly so as to lower the cutting edge 14.

When the bucket has been filled to a level above the damper shaft 31, the lead rope 16 is slackened and the return rope 17 is reeled in. This tilts the bail 20 upwardly and rearwardly until the legs thereof strike the stop members 23. The entire bucket will then be swung upwardly as a unit with the bail 20 until the vertical position of Fig. 5 is reached, at which time the weight of the bucket and its contents will rest upon the end plate 13. Further rearward movement of the return rope 17 tilts the bucket rearwardly to the broken-line position of Fig. 6, allowing the weight to rest upon the rollers 29.

The hoist continues to reel in the return rope 17 and the tail rope 18, and to pay out the lead rope 16 so as to draw the bucket upwardly along the stope 35 and ramp 39 until the hopper opening 36 is reached. This removes the support from the rollers 29, allowing the entire bucket to swing downwardly to the full-line position of Fig. 6 to dump the contents into the cars 37. The bucket is supported by means of the bail 20 and the trailing extremities 22.

The return rope 17 is now tightened to elevate the bail, and the lead rope is reeled in to swing the bail forwardly and downwardly to the original position of Fig. 4. The tail rope 18 is also reeled in to pull the end 13 of the bucket forwardly, so as to turn the bucket back to the original position of Fig. 4 to receive another load.

It is desired to call attention to the fact that when the bucket swings from the position of Fig. 4 to the solid-line position of Fig. 6, the free-swinging damper plate 34 will maintain a substantially vertical position at all times, so as not to interfere with the discharge of material from the bucket.

If the bucket is used on a level surface or for ordinary dragline work, the damper plate 34 is not necessary and can be quickly and easily removed by simply withdrawing the cotter keys 33.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. In a slusher bucket, a bucket open at its front, a tail rope connected with the rear end of said bucket, a U-shaped bail straddling said bucket and having a bridge and arms extending rearwardly from the bridge along opposite sides of the bucket, pivot members pivotally connecting the opposite side walls of the bucket with the arms of said bail and pivotally mounting the bucket for tilting movement through the bail, a lead rope and a return rope connected with the bridge of said bail, and stop members projecting outwardly from the side walls of the bucket forwardly of the pivot members and over the bail in position to be engaged by the arms of said bail when the bail is swung upwardly and rearwardly so as to tilt the bucket and the bail to an inverted position, the pivot members then pivotally mounting the bucket for downward tilting movement through the bail to a dumping position.

2. The structure set forth in claim 1, wherein the arms of the bail have rear end portions extending from the pivot members and projecting beyond the rear end of the bucket and adapting the bail to serve as a fulcrum upon which the bucket swings from its normal position toward an inverted position.

3. The structure set forth in claim 1, wherein the bucket has its rear wall arcuate vertically between the top and bottom of the bucket, said bail having the rear ends of its arms projecting beyond the arcuate rear wall and serving as a fulcrum upon which the bucket tilts upwardly and rearwardly on its arcuate rear wall and then continues its tilting movement rearwardly and downwardly to an inverted position in which the bucket has its top presented downwardly.

4. The structure set forth in claim 1, wherein the bucket has its rear wall arcuate between the top and the bottom of the bucket and upon which the bucket has tilting movement rearwardly and downwardly to an inverted position presenting its top downwardly, and rollers extending across the top transversely thereof and rotatably mounted and upon which the bucket is supported when in its inverted position.

JOHN O. PITTS.
